Company, a corporation of Pennsylvania

Application May 8, 1947, Serial No. 746,832

18 Claims. (Cl. 214—75)

1

This invention relates to timber setting machines, and more particularly to an improved machine for setting mine timbering elements, such as horizontal cross timbers, in an underground mine or tunnel.

In underground mining or tunneling, horizontal cross timbers are placed against the roof as the work advances, and the cross timbers are set in position by uprights or props, or by rib pinnings. Such setting of the cross timbers is usually effected manually, and is an extremely hazardous, arduous and time-consuming task. Also, the timbers and props must be transported long distances in the mine or tunnel. Machines have previously been employed for mechanically setting the cross timbers, but such machines are limited in operating range, are relatively high and bulky, and do not have sufficient timber and prop carrying capacity or must carry the timbers and props on separate trailers. The present invention contemplates improvements over such known machines in that extreme compactness is attained while providing a relatively large timber and prop carrying capacity within the machine itself, and also a relatively wide range of operation and increased flexibility are obtained. By the provision of such a machine, the cross timbers are moved up against the mine or tunnel roof and firmly held there during setting of the timbers, thereby making the task of timber setting relatively easy and minimizing the danger.

It is accordingly an object of the present invention to provide an improved timber setting machine whereby the disadvantages of previous machines are substantially overcome. Another object is to provide an improved timber setting machine having, within itself, a relatively large timber and prop carrying capacity. Yet another object is to provide an improved timber setting machine having a relatively wide operating range. A further object is to provide an improved adjustable timber supporting structure for receiving and supporting a cross timber and for elevating the timber to bring the latter up against the roof and for holding it there during setting thereof. A still further object is to provide an improved timber setting machine having a machine body provided with a relatively large timber and prop carrying compartment arranged in a relatively low position and of substantial width and height whereby a relatively large number of mine timbers and props can be transported while maintaining the overall height of the machine relatively low, thereby enabling the machine to operate in mines or tunnels having relatively low head

2

room. Still another object is to provide an improved timber setting machine having an improved adjustable timber receiving, supporting and elevating structure mounted and arranged in a novel manner with respect to the timber and prop carrying compartment whereby not only a large load can be carried, but also affording a relatively wide range of adjustment. A further object is to provide an improved adjustable supporting structure mounted on the machine body for horizontal adjustment whereby timbers may be supported at either side of the machine body as well as crosswise at one end of the machine body. Still another object is to provide improved adjustable timber guides for guiding the timbers loading of the body-compartment and for directing a timber from the compartment onto the turntable or saddle of the adjustable timber support. A still further object is to provide an improved extensible elevating jack structure for supporting and elevating a timber, together with a floor-engaging jack for holding the parts firmly in position during operation thereof. It is a further object to provide an improved timber setting machine having an improved arrangement and combination of parts. These and other objects and advantages of the invention will, however, hereinafter more fully appear.

In the accompanying drawings there is shown for purposes of illustration one form which the invention may assume in practice.

In these drawings:

Fig. 1 is a top plan view of a timber setting machine constructed in accordance with a preferred illustrative embodiment of the invention.

Fig. 2 is a side elevational view of the machine shown in Fig. 1.

Fig. 3 is an enlarged view in central longitudinal vertical section taken substantially on line 3—3 of Fig. 1.

Fig. 4 is an enlarged vertical sectional view taken on the plane of Fig. 3, showing details of the front jack structures.

Fig. 5 is an enlarged vertical sectional view taken on the plane of Fig. 4, showing the floor jack.

Fig. 6 is an enlarged cross sectional view taken substantially on line 6—6 of Fig. 1, and showing the rear guide roller device.

Fig. 7 is a vertical sectional view similar to Fig. 4, showing the elevating and floor-engaging jacks in extended position.

Fig. 8 is a vertical sectional view taken substantially on line 8—8 of Fig. 7.

Fig. 9 is a detail sectional view taken on line 9—9 of Fig. 3.

Fig. 10 is a detail sectional view taken on line 13-10 of Fig. 9.

Fig. 11 is an enlarged fragmentary vertical sectional view taken on line 11-11 of Fig. 1, illustrating the front guide roller device.

Fig. 12 is a horizontal sectional view taken substantially on line 12-12 of Fig. 3.

Fig. 13 is a diagrammatic view illustrating the hydraulic system.

Figs. 14 and 15 are respectively diagrammatic side and end views, showing the machine in an operating position in a mine or tunnel.

Fig. 16 is a diagrammatic plan view showing the machine in a position to set a cross timber parallel with a rib in preparation to the starting of a cross cut.

In the illustrative embodiment of the invention, as shown in the drawings, the improved timber setting machine is preferably of the rubber tired, wheel mounted type especially designed for use in setting roof timbers or cross bars in trackless mines or tunnels. Evidently, the machine may be mounted in other manners and used for other purposes.

The machine comprises a low compact body 1 mounted on rubber tired wheels adapted to travel over the floor of a mine or tunnel, and the rear wheels 2, 2 are traction wheels and are driven by suitable motors, preferably electric motors, 3, 3 through suitable transmission connections 4, 4. The front wheels 5, 5 are steering wheels and are swiveled in a conventional manner to turn horizontally and are provided with suitable fluid operated steering gear controlled by a hand wheel 6 located in a recess providing the operator's station at one side of the front end of the machine body. A motor 7, likewise preferably an electric motor, drives a pump to be later described. Extending centrally lengthwise of the machine body is a timber carrying compartment 8 of substantial width and height. Mounted on the machine body beneath the compartment for swinging on a vertical axis and extending outwardly beyond the rear end of the body is a horizontal support 9 carrying, at its outer extremity, an elevating jack structure 10 which supports a horizontal timber receiving support or saddle 11. The load carrying compartment 8 is adapted to receive a load of mine timbering elements such as cross timbers and props, and a guide roller device 12 is arranged at the front end of the compartment for facilitating loading of timbers. When the support or saddle is properly positioned, a timber may be moved lengthwise from the compartment over a rear guide roller device 12' onto the support. The jack 10 may be operated slightly to raise the saddle above the top of the machine body and the timber may then be turned with the saddle into a position crosswise of the machine body at the rear of the latter. The jack 10 may then be operated to elevate the saddle to bring the timber up against the roof and to hold it there during setting of the uprights or props, or during insertion of the rib pins. Arranged in a recess at the opposite side of the front end of the machine from the operator's station is a conventional cable reel mechanism 13 for the power conductor cable through which power is conducted to the electric motors 3, 3 and 7; and this reel is driven in winding direction by a conventional hydraulic motor 13'. At one side of the rear end of the machine body is an electrical control apparatus 14 for the electric motors, while at the opposite side of the rear end of the

body is a power saw 15, driven by a hydraulic motor 16. The traction wheel and pump driving motors, the steering mechanism, the cable reel mechanism, electrical control apparatus and the power saw may be similar to those fully described in a copending application to C. F. Ball et al., Serial No. 746,646, filed May 8, 1947.

The machine body is preferably of a fabricated, welded construction and has vertical plates 17, 17 extending longitudinally of and spaced equi-distantly from the longitudinal center of the machine body, and these plates form the sides of the load carrying compartment 8. The compartment bottom is formed by a bottom plate 18, so positioned that the compartment bottom is in a relatively low position below a horizontal plane including the wheel axes, and the wheel axles, which are herein drop axles, extend transversely beneath this bottom plate. The horizontal swinging support 9 is herein preferably in the form of a bell crank with one arm 20 projecting rearwardly from the machine body and at its outer end supporting the extensible jack structure, and this arm has a forward bearing support 21 swiveled on a vertical pivot shaft 22 suitably secured to the bottom plate 18 midway between the plates 17, at the longitudinal vertical center of the machine. Projecting laterally from one side of the bearing support 21 at substantially right angles to the arm 20 is a shorter arm 23 to which the rear end of a link 24 is pivotally connected at 25. This link extends longitudinally forwardly beneath the compartment bottom and is pivotally connected at 26 at its front end to one end of a lever 27, the latter in turn pivotally mounted at 28 on a bracket 29 suitably secured to the adjacent side plate 17. Secured to a cross plate 30 integral with the machine body is a bracket 31 to which is pivoted, at 32, a horizontal fluid cylinder 33, also located beneath the compartment bottom. Reciprocable in this cylinder is a piston 34 having its piston rod 35 projecting rearwardly through the packed rear cylinder head and pivotally connected at 36 at its rear end to the lever 27. Thus, when the piston is moved in the fluid cylinder, the rearwardly projecting arm 20 may be swung through the lever 27, link 24 and arm 23 horizontally from one side of the machine body to the other, and the lower rearward portions of the plates 17 are cut away at 37 to permit a wide range of horizontal swing, to locate the saddle beyond the sides of the machine body. The machine body has a horizontal rearward projection 38 having a rearward arcuate end 39, and the arm 23 has a vertical portion 40 which supports upper and lower projections 41 and 42, which respectively overlie and underlie the curved end 39 of projection 38 for guiding the arm during horizontal swinging thereof and to provide a rearward arm support. The timber elevating jack 10, carried at the outer extremity of the horizontal arm 20, may assume various forms and herein comprises a vertical fluid cylinder 45 having a flange 46 secured, as by screws, to the upper surface of the vertical outer portion 40 of the horizontal arm 20; and the lower portion of this cylinder is arranged in a vertical opening 47 in the vertical arm portion 40, as shown in Fig. 4. Contained in the vertical cylinder 45 is a series of cylinder and piston sections 48, 49 and 50, herein arranged in telescopic relation and each having a piston portion and a tubular piston rod portion. Reciprocable in the bore 51 of the inner section 50 is a piston 52 having a piston rod 53.

The outer cylinder 45 and the sections 48, 49 and 50 carry suitable packings 54, 56, 56 and 57, sealingly engaging the several piston rod peripheries to prevent leakage. The means for supplying fluid to and exhausting fluid from these cylinders will later be fully explained. The inner piston rod 53 has a circular upper portion 58 resting, when the jack is collapsed, on the upper end of the inner section 50, and projecting upwardly from this circular portion is a threaded projection 59 which is threadedly secured to a bottom plate of a tiltable spring mounting 60, which carries a horizontal frame 61 of the timber receiving support or saddle 11. By the provision of this spring mounting, the saddle may have limited endwise tilt relative to the jack to compensate for the unevenness of the roof against which a timber or cross bar is placed. If desired, the timber support or saddle may be swivelled to turn relative to the piston rod 53. This saddle has an upper plane timber receiving and supporting surface 62 and upstanding side flanges 63, 63 engageable with the sides of a timber on the support to prevent lateral displacement of the timber with respect to the supporting surface 62. The timber support or saddle may be turned with the inner piston rod and piston about the vertical axis of the elevating jack, relative to the supporting arm 20. Arranged in a vertical opening 65 in the vertical support 40 of the arm, rearwardly of the elevating jack, is a vertical fluid cylinder 66 containing a reciprocable piston 67, the latter having its piston rod 68 projecting downwardly through the lower packed head 69 of the cylinder. A foot piece 70 has a universal connection at 71 with the lower end of the piston rod 68, and the universal connection is herein preferably of the ball and socket type. The lower surface of the arm 20 is recessed at 72 to receive the foot piece when the piston is in its elevated retracted position, as shown in Fig. 4. Attached at 73 to the upper cylinder head 74 and at 75 to the lower end of the piston rod is a preloaded coil spring 76 for holding the foot piece in its elevated retracted position. Evidently, the floor engaging jack may be arranged coaxially with the elevating jack, if desired. Also other types of elevating and floor engaging jacks may replace those disclosed, for example, power operated screw jacks.

The roller guide device 12 comprises, as shown in Fig. 11, vertical plates 77 secured to the inner sides of the side plates 17 at the front end of the machine body, and the plates 77 have series of angularly disposed notches 78 for receiving the ends of a transverse guide roller 79 extending substantially across the load compartment. Thus the guide roller may be placed at different heights to facilitate loading of timbers at different heights into the body compartment. The timber guide 12 for guiding a timber during its movement onto the support 61 comprises a horizontal guide roller 80 extending substantially across the rear end of the load compartment between the side plates 17, as shown in Fig. 6, and this roller is journaled at its ends on bearing sleeves 81 supported by a transverse shaft 82. The shaft 82 is keyed at its ends at 83 to guide blocks 84, guided for vertical adjustment in vertical guideways 85 formed in the side plates 17. Attached at 86 to each of these guide blocks is an endless chain 87, and these chains are arranged at the outer sides of the plates 17, as shown in Fig. 6, and engage sprockets 88, 89 secured to the opposite ends of an operating shaft 90. This shaft 75

extends horizontally across the compartment 8 near the bottom thereof and is journaled at its ends in bearings 90 suitably supported within the side plates 17. Journaled within the upper portion of one of the side plates 17 at 91 and in a bracket 92, herein mounted on the top of the control apparatus 14, is a horizontal operating shaft 93 having a handwheel 94. Keyed to this shaft is a sprocket 95 which engages one of the chains 87. The other chain 87 engages an idler sprocket 96 journaled on a shaft 97 secured to the adjacent side plate 17. Thus, when the shaft 93 is rotated by the handwheel 94, it imparts rotation through one of the chains 87 to the shaft 90, and this latter shaft effects rotation of the sprocket 89, thereby to drive the other chain. As the chains 87, 87 are concurrently actuated, the guide blocks 84 are moved in unison in the guideways 85, thereby to raise or lower the guide roller 80. A conventional ratchet and pawl device 98 is provided for the shaft 93 to hold the roller 80 in its adjusted position, and during lowering of the roller, the pawl is disengaged from the ratchet teeth. It will be evident that the shaft 93 may be power driven if desired, and that the roller may be adjusted by other types of adjusting devices. If desired, a roller guide device 12 may be employed at the rear end of the compartment in lieu of the roller guide device 12, and, conversely, a guide device 12 may be used at the front end of the compartment in place of the guide device 12.

Now referring to the hydraulic system shown diagrammatically in Fig. 13, it will be noted that the pump driven by the motor 7 is designated 100 and has its intake connected by a conduit 101 to a tank or reservoir 102, herein containing a liquid, preferably a light lubricating oil. The pump discharge is connected by a conduit 103 to the supply passage of a valve box 104 of a conventional valve mechanism 105. The discharge passage of the valve box is connected by a conduit 106 back to the tank. The valve box is herein preferably made up of four sections, and the sections 107, 108 and 109 have bores containing conventional slide valves 110, 111 and 112 respectively, of the balanced spool type, and respectively having suitable operating handles. The valve box section 107 contains a conventional relief valve 114. The bore of the section 107 is connected by conduits 115 and 116 to the opposite ends of the arm swing cylinder 33 so that fluid may be supplied to either end of the cylinder through the pressure conduit 103, while the other end is connected to discharge through the discharge conduit 106. When the valve is in neutral position, both conduits 115, 116 are closed, trapping the liquid in the cylinder 33 to lock the piston 34 against movement, thereby firmly to hold the arm 20 in adjusted position. The bore of the valve box section 108 is connected to a conduit 117, which passes through the arm 20, as shown in Figs. 4 and 7, and this conduit leads to a hand valve device 118 mounted on the frame portion 40 at the outer portion of the arm 20, near the floor jack, as shown. The section 109 is connected to a conduit 119, also passing through the arm 20, and which likewise leads to the valve device 118. The conduits 117 and 119 respectively have check valves 120 and 121 to permit fluid flow toward the valve device 118 but to prevent reverse flow. The valve device 118 may assume various forms, but herein comprises a horizontal casing 122 having end chambers 123 and 124 connected by a transverse passage 125. A conduit 126 connects the end chamber 123 to

the upper end of the fluid cylinder 45 of the elevating jack 10, and a conduit 127 connects the other end chamber 124 to the upper end of the fluid cylinder 66 of the floor engaging jack. A return conduit 128, also passing through the arm 20, connects the passage 125 with the suction conduit 101. Hand operated valves 129 and 130, herein of the end-seating type, independently control the communication of the passage 125 with the end chambers 123 and 124 respectively. The conduits 117 and 119 and 128 may have flexible portions (not shown) which extend outward from the arm 20 near its swivel bearing so that the arm may swing without interfering with the conduits in an obvious manner. So that fluid may flow to the lower end of the cylinder 45 beneath the pistons of the elevating jack 10, the piston element 48 has vertical passages 131 in the piston head thereof, permitting flow from the cylinder bore at the upper side of the piston head to the cylinder bore beneath the piston head. The walls of the several piston rod elements are perforated at 132 to preclude trapping of fluid that may leak past the several piston heads into the upper ends of the several cylinder bores. A suitable shield or housing 133 encloses the fluid cylinder 66 and the valve device 118 and is provided with side openings to permit access to the handles of the hand valves 129 and 130. When the hand valves 129 and 130 are closed, fluid may flow, under the control of the slide valves 111 and 112, through conduits 117 and 119, through the end chambers 123 and 124 of the valve device 118, and thence through conduits 125 and 127 to the elevating and floor jacks. When the slide valves 111 and 112 are returned to neutral position, the check valves 120 and 121 automatically prevent reverse fluid flow from the elevating and floor jacks, and when the valves 129 and 130 are opened, the elevating and floor jack cylinders are connected to the suction side of the pump through passage 125 and conduits 123 and 101, to thereby effect rapid retraction of the elevating and floor jacks. Thus, the valve device 118 may serve to vent the jack cylinders and the valves 129 and 130 thereof are normally closed during operation of the jacks. Extension of the jacks is controlled by the slide valves 111 and 112 and the automatic check valves 120 and 121 serve, by precluding reverse flow, to lock the jacks in extended position when the valves 111 and 112 are returned to neutral position. Evidently, the valve device 118 may be constructed to vent the jack cylinders in other manners, as for example, directly back to the liquid reservoir.

The general mode of operation of the improved timber setting machine is as follows: The body compartment 8 is loaded with mine timbering elements, such as cross timbers and props, and the front roller guide device 12 may have its guide roller 79 positioned at the desired height to facilitate loading of the timbering elements into the compartment. When the body compartment is loaded, the swingable support 9 and the timber elevating and floor engaging jacks are moved to their transport position shown in Figs. 1 and 2, and the motors 3, 3 may be operated to drive the traction wheels 2, 2 to effect propulsion of the machine along the mine passageways or tunnel. Steering of the machine is effected by the steering wheels 5, 5 under the control of the handwheel 6. When the machine is moving through a mine passageway or tunnel where there is no overhead trolley wire or other source of electric power, the conductor cable of the cable reeling

mechanism 13 is attached to the trolley wire or other power source in the main entry, and as the machine moves inwardly toward the heading, the conductor cable is pulled off of the reel with the cable under suitable tension. When the working face of the heading is reached and it is desired to set a cross timber, the timber support or saddle 11 is turned with the piston rod 53 about the vertical axis of the elevating jack 10 to a longitudinally extending position, as shown in Fig. 3, to receive a timber moved lengthwise from the timber compartment, and the transverse guide roller 80 is adjusted vertically in the compartment to the desired height, thereby properly to receive the timber so that the latter may be easily moved outwardly onto the timber support 11. The timbers are usually piled up on top of one another in the compartment, and the guide roller 80 may be positioned to receive and guide a timber piled at any height. When a timber is positioned centrally on the timber support 11, the jack 10 may be operated under the control of the slide valve 111 to raise the timber support or saddle slightly above the machine body and the timber may then be turned with the saddle about the vertical axis of the elevating jack into a position crosswise of the machine body, as indicated in dotted lines in Fig. 15. With the pump driving motor 7 running to cause the pump 100 to supply liquid under pressure to the valve box 104, the slide valve 110 may be moved to a position to supply liquid under pressure to one end or the other of the arm swing cylinder 33 to swing the arm 20 horizontally about its pivot to the desired position with respect to the rear end of the machine body (one lateral position of the arm being shown in Fig. 16), and the slide valve 110 may thereafter be positioned to trap the liquid in the cylinder 33, rigidly to lock the horizontal arm 20 in adjusted position. The slide valve 111 may then be positioned to supply liquid under pressure past the check valve 120 and the valve device 118 (it being understood that the valves 129 and 130 are at this time in closed seated position) to the cylinder 45 of the elevating jack 10 to move the jack sections 48, 49, 50 and 53 upwardly to elevate the saddle 11 to bring the cross timber supported thereby up against the roof (see Figs. 14 and 15), and the check valve automatically traps the liquid in the elevating jack when the slide valve 111 is returned to its neutral position. The slide valve 112 may then be positioned to supply liquid under pressure past the check valve 121 and the valve device 118 (with the valves 129 and 130 still closed) to the upper end of the cylinder 66 of the floor engaging jack to lower the footpiece 70 into firm engagement with the floor. The check valve 121 traps the liquid in the floor jack cylinder when the slide valve 112 is returned to neutral position to lock the jack piston in position. The elevating jack holds the cross timber firmly in position up against the roof during setting of the uprights or props, or during insertion of the rib pins. The elevating jack 10 is sufficiently powerful and is so rigidly braced by the floor engaging jack that a cross timber may be firmly held in place during setting thereof even when a loose roof or roof falls are present, and accidental dropping of the timber due to collapse of the elevating jack is prevented by the check valve 120 in the event the liquid supply should fail for any reason. When the valves 129 and 130 of the valve device 118 are opened, liquid is discharged from the jacks through the passage 125 and the conduit 128 connected to the conduit 101 leading to

the suction side of the pump; and due to the suction created within the elevating jack cylinders, the jacks are rapidly collapsed. The spring 76 aids in the retraction of the floor jack piston, and holds retracted the footpiece 70. When the supporting arm 20 and the elevating and floor engaging jacks have been returned to their transport position shown in Figs. 1 and 2, the driving motors 3, 3 for the traction wheels may be reversed to propel the machine outwardly away from the working face, and as the machine moves forwardly, the hydraulic motor 13' drives the cable reel 13 in the direction to wind in the conductor cable in a well known manner. As described in the application above referred to, the power saw 15 may be operated to cut the timbers and props to the desired lengths, and during the sawing operation, propulsion of the machine is automatically precluded. In Fig. 16, the machine and horizontal arm are so positioned in the mine or tunnel passageway that a cross timber may be set against the roof in substantial parallelism with a rib so as to support the roof at the beginning of a cross cut. It will be evident that the horizontal arm and timber elevating jack may be located to support a timber at either side of the machine body, thereby reducing the necessity of frequent maneuvering of the machine during setting of cross timbers at various locations against the roof.

As a result of this invention, an improved timber setting machine is provided whereby cross timbers may be quickly set in place with comparative ease and with the hazards usually encountered substantially eliminated. By the provision of the horizontally swingable supporting arm and the extensible jack structure carried thereby, a relatively wide range of adjustment is afforded whereby a timber may be set against the roof at either side of the machine as well as crosswise at one end of the machine. The extensible elevating jack for the cross timbers affords an extremely simple and powerful means for elevating the timbers, and the floor engaging jack serves to provide an extremely stable bottom support. By the provision of the adjustable guide roller at the rear end of the timbering element receiving compartment, a timber may be easily moved from the compartment onto the timber support, and the guide roller at the front end of the compartment aids in loading of timbers into the compartment. By mounting the timber supporting structure on the machine body beneath the timber and prop carrying compartment, not only is an extremely sturdy support provided for the supporting structure, but also a timber and prop carrying compartment of relatively large capacity is attained. Other manners of use and advantages of the improved timber setting machine will be clearly apparent to those skilled in the art.

While there is in this application specifically described one form which the invention may assume in practice, it will be understood that this form of the same is shown for purposes of illustration and that the invention may be modified and embodied in various other forms without departing from its spirit or the scope of the appended claims.

What we claim as new and desire to secure by Letters Patent is:

1. In a timber setting machine, the combination comprising a portable body having a horizontal supporting surface arranged centrally between its sides and extending longitudinally,

thereof and adapted to receive a load of mine timbers with the latter extending generally lengthwise of said body, a timber-receiving saddle arranged at one end of said body and positionable to receive a timber moved endwise from said body, and an adjustable supporting structure for said saddle mounted on said body in spaced relation to said timber supporting surface and including a horizontal support adjustable horizontally relative to said body from one side thereof to the other while said body remains stationary to locate said saddle in different lateral timber supporting positions, means for confining said horizontal support to adjustment in horizontal planes with respect to said body, said supporting structure also including an extensible, vertical power elevating jack mounted on said horizontally adjustable support and by which said saddle is carried for elevating said saddle in any horizontal position of adjustment of said support relative to said body to move a timber supported by said saddle vertically up against a mine roof and to hold it there during setting of said timber.

2. In a timber setting machine, the combination comprising a portable body having a horizontal supporting surface centrally between its sides and adapted to receive a load of mine timbers with the latter arranged side by side in substantial parallelism generally lengthwise of said body, a timber-receiving saddle disposed at one end of said body, and an adjustable supporting structure mounted on said body at a point spaced from said load-receiving surface and by which said saddle is carried, said supporting structure including an extensible, vertical power elevating jack on which said saddle is mounted and an adjustable support for said jack for adjusting the latter horizontally across one end of said body for locating said timber-receiving saddle selectively in different lateral positions whereby any one of the substantially parallel timbers may be moved endwise from said body onto said saddle without bodily lifting of the timber, and means for operating said jack to elevate said timber-receiving saddle vertically relative to said body and to said adjustable support to bring a timber supported by said saddle up against a mine roof and for holding it there during setting of the timber.

3. In a timber setting machine, the combination comprising a portable body having a centrally located compartment of substantial width and depth extending longitudinally thereof, said compartment having a horizontal bottom disposed in a relatively low position on said body and upright parallel sides extending to the top of said body, said compartment adapted to receive a load of mine timbers with the latter arranged side by side in substantial parallelism generally lengthwise of said body, an adjustable supporting and elevating structure mounted on said body and including a horizontal support pivotally mounted at its inner end on said body outside of said compartment to swing horizontally relative to said body, and a timber-receiving saddle disposed at one end of said body beyond one end of said compartment and carried by said swingable support at its outer end and positionable, by horizontal swinging adjustment of said swingable support, selectively into different lateral positions across the end of said compartment whereby any one of said substantially parallel timbers may be moved endwise from said compartment onto said saddle without bodily lifting of the timber.

11

4. In a timber setting machine, the combination comprising a portable body having a centrally located compartment of substantial width and depth extending longitudinally of said body, said compartment having a horizontal bottom 5 and upright parallel sides and adapted to receive a load of mine timbers with the latter arranged in substantial parallelism generally lengthwise of said body, a horizontal arm pivotally mounted at its inner end on said body beneath the bottom of said compartment and extending outwardly beyond one end of said compartment at one end of said body, means for confining said arm to swinging movement in horizontal planes with respect to said body, and a timber-receiving saddle carried by said arm at its outer end and positionable, by horizontal swinging adjustment of said arm, selectively into different lateral positions across said end of said compartment into alignment with any one of the parallel timbers to permit any one of the timbers to be moved endwise from said compartment onto said saddle without bodily lifting of the timber.

5. A timber setting machine of the character set forth in claim 4 wherein an adjustable supporting and elevating means is carried by said arm for elevating said saddle relative to said body and to said arm to bring a timber supported by said saddle up against a mine roof and to hold it there during setting of the timber.

6. A timber setting machine of the character set forth in claim 5 wherein said adjustable supporting and elevating means carried by said arm consists of a vertically disposed, extensible, power jack arranged at the outer end of said arm for elevating said saddle vertically along a straight path for the purpose specified.

7. In a timber setting machine, the combination comprising a portable body adapted to carry a load of piled-up, superimposed mine timbers arranged in substantial parallelism generally longitudinally of said body, a timber-receiving and supporting saddle arranged at one end of said body, a laterally adjustable support on said body for supporting said saddle in different lateral positions to receive a timber moved endwise from said body, and a guide on said body and adjustable vertically into different heights relative to said body and to said support for receiving the adjacent end of any one of said piled-up mine timbers for guiding the timber as it is moved endwise from said body onto said saddle, said support being adjustable laterally relative to said body to locate said saddle into different lateral timber-receiving positions, and said adjustable guide being of sufficient length transversely of said body as to guide a timber moved endwise from said body onto said saddle irrespective of the laterally adjusted position of the latter relative to the timber-load.

8. In a timber setting machine, the combination comprising a portable body having a centrally located compartment of relatively large capacity extending lengthwise thereof and adapted to receive a load of mine timbers with the latter arranged generally longitudinally of said body, a timber-receiving saddle mounted on said body and located at one end of said body outwardly beyond said compartment, said saddle movable laterally into different timber receiving positions across the end of said compartment, a guide roller arranged on said body and extending transversely across the adjacent end of said compartment and spaced from said saddle for

guiding a timber moved endwise from said compartment onto said timber-receiving saddle in any of said lateral positions of said saddle, and means for elevating said saddle vertically relative to said body and to said guide roller to bring a timber on said support upwardly against a mine roof.

9. In a timber setting machine, a portable body having a compartment adapted to receive a load of superimposed mine timbers, a timber receiving support mounted on said body and arranged near the top of said compartment beyond one end of the latter, a guide roller arranged on said body transversely of said end of said compartment and spaced from said support for guiding the adjacent end of a timber supported thereby, and mechanism for adjusting said roller in a vertical direction relative to said body into positions to guide timbers disposed at different heights in said compartment, said roller when properly positioned with respect to said timber receiving support serving to guide a timber as it is moved lengthwise from said compartment onto said timber receiving support.

10. In a timber setting machine, the combination comprising a portable body adapted to carry a load of mine timbers with the latter extending generally lengthwise of said body, a timber-receiving saddle arranged at one end of said body and adapted to receive a timber moved endwise from said body, an adjustable supporting and elevating structure mounted on said body and by which said timber-receiving saddle is carried for adjusting said saddle vertically relative to said body to raise a timber thereon up against a mine roof, said supporting and elevating structure including a supporting element projecting horizontally from said end of said body and at the outer end of which said vertically adjustable timber-receiving saddle is carried, and a co-operating floor-engaging support which is normally elevated during transport of the machine and which is movable into lowered supporting position against the mine floor to provide a bottom brace for said projecting supporting element during elevation and setting of a timber.

11. In a timber setting machine, the combination comprising a portable body adapted to carry a load of mine timbers with the latter extending generally lengthwise of said body, a timber-receiving saddle arranged at one end of said body for receiving a timber moved endwise from said body, and an adjustable supporting structure mounted on said body and by which said saddle is carried and adjustable horizontally relative to said body for positioning said saddle laterally across said end of said body and adjustable vertically for elevating said saddle vertically to bring a timber thereon up against a mine roof, said supporting structure including a horizontal arm pivotally mounted at its inner end on said body to swing horizontally relative thereto and by which said saddle is carried, and a normally retracted, floor-engaging support carried at the outer end of said arm and movable into engagement with the mine floor to provide a bottom brace for said arm during elevation and setting of a timber.

12. In a timber setting machine, the combination comprising a portable body adapted to carry a load of mine timbers with the latter extending generally lengthwise of said body, a timber-receiving and supporting saddle arranged at one end of said body, a horizontal arm pivotally mounted at its inner end on said

13

body to swing horizontally relative thereto from one side of said body to the other, an extensible vertical power jack carried at the outer end of said arm and by which said saddle is carried for vertically elevating said saddle to move a timber thereon up against a mine roof, and a normally retracted floor-engaging support carried by the projecting end of said arm and movable below said arm into engagement with the mine floor for bracing said arm during holding of a timber up against the mine roof.

13. In a timber setting machine, the combination comprising a portable body having a compartment of relatively large capacity located centrally between its sides and adapted to receive a load of mine timbers with the latter arranged in side by side substantially parallel relation generally lengthwise of said body, a timber-receiving saddle swivelly mounted to turn about a vertical axis and arranged at one end of said body, said saddle positionable on its swivel to receive a timber moved endwise from said compartment, and an adjustable supporting structure mounted on said body outside of said compartment and including a support by which said saddle is carried for adjusting said saddle laterally across said end of said body selectively into different timber-receiving positions whereby any one of the substantially parallel timbers may be moved endwise from said compartment onto said saddle without bodily lifting of the timber, and said supporting structure including elevating means for raising said saddle vertically along a straight path in any of its laterally adjusted positions whereby a timber on said saddle may be moved up and held against the mine roof.

14. In a timber setting machine, the combination comprising a portable body having a relatively large compartment arranged centrally between its sides and adapted to receive a load of mine timbers with the latter arranged side by side in substantial parallelism and extending generally longitudinally of said body, said compartment having a horizontal bottom and upright parallel sidewalls, a timber-receiving saddle disposed at one end of said body beyond one end of said compartment and located when in lowered position near the top of said compartment, and an adjustable supporting structure for said saddle for supporting the latter and including a support mounted on said body for adjustment horizontally relative thereto to locate said saddle in different lateral timber receiving positions with respect to said end of said compartment whereby any one of the substantially parallel timbers may be moved endwise from said compartment onto said saddle without bodily lifting of the timber, said supporting structure including elevating means for said saddle for raising the latter vertically along a straight path relative to said body to a relatively high position above said body irrespective of the laterally adjusted position of said saddle thereby to move a timber on said saddle up against a mine roof.

15. In a timber setting machine, the combination comprising a portable body having a compartment of relatively large capacity located centrally between its sides and adapted to receive a load of mine timbers with the latter extending in substantial parallelism generally lengthwise of said body, said compartment having a horizontal bottom and upright parallel sidewalls, a timber-receiving saddle disposed at

14

one end of said body beyond one end of said compartment and when in lowered position located near the top of said compartment, an adjustable supporting structure mounted on said body for supporting said saddle and adjustable horizontally relative to said body to locate said saddle in different lateral positions with respect to said compartment whereby any one of the substantially parallel timbers may be moved

- 10 endwise from said compartment onto said saddle, and guiding means on said body near the adjacent end of said compartment and spaced longitudinally of said body with respect to said saddle and relative to which said saddle is laterally adjustable for guiding a timber as it is moved endwise from said compartment onto said saddle in all laterally adjusted positions of the latter with respect to said end of said compartment.

- 20 16. In a timber setting machine, a portable body adapted to carry a load of mine timbers, said body having an outer curved end providing an arcuate guide, a horizontal arm pivotally mounted on said body and projecting outwardly beyond one end thereof, guiding means on said arm engaging said guide for guiding said arm during horizontal swinging thereof, a timber receiving and supporting saddle, and an elevating structure carried by said arm for elevating said saddle.

- 30 17. In a timber setting machine, the combination comprising a portable body adapted to carry a load of mine timbers extending generally lengthwise of said body centrally between the sides of the latter, a horizontal arm pivotally mounted at its inner end on the bottom of said body to swing in horizontal planes below the timber load and projecting outwardly beyond one end of said body, means for swinging said arm horizontally about its pivot to move its outer end from one side of said body to the other, an extensible vertical power elevating jack carried at the outer end of said arm, and a timber-receiving saddle carried by said jack and adapted to receive a timber moved endwise from said body and to elevate the timber up against the mine roof, said jack positionable by horizontal swinging movement of said arm across said end of said body to receive timbers moved endwise from said body at different lateral locations.

- 40 18. In a timber setting machine, the combination comprising a portable body having a compartment of relatively large capacity adapted to carry a load of mine timbers with the latter arranged in substantial parallelism generally lengthwise of said body, said compartment having a horizontal bottom disposed in a relatively low position on said body and upright parallel sidewalls extending to the top of said body, a horizontal arm pivotally mounted at its inner end on said body to swing in horizontal planes below the bottom of said compartment and projecting outwardly beyond one end of said compartment at one end of said body, power operated mechanism arranged beneath said compartment-bottom for swinging said arm horizontally about its pivot to move the outer end of said arm laterally across said end of said body, an extensible vertical power elevating jack carried at the outer end of said arm, and a timber-receiving saddle carried by said jack and positionable by horizontal swinging movement of said arm in different positions laterally of said end of said compartment whereby any one of the

15

substantially parallel timbers may be moved end-wise from said compartment onto said saddle, and said elevating jack being operable to raise said saddle vertically to bring a timber on said saddle upwardly against the mine roof.

LLOYD G. FELDERMAN.
